DESIGN FOR A HARMONICA

John Vassos, New Canaan, Conn., assignor to M. Hohner, Inc., New York, N. Y., a corporation of New York

Application April 1, 1939, Serial No. 83,991

Term of patent 14 years

To all whom it may concern:

Be it known that I, John Vassos, a citizen of the United States, residing at New Canaan, in the county of Fairfield and State of Connecticut, have invented a new, original, and ornamental Design for a Harmonica, of which the following is a specification, reference being had to the accompanying drawing, forming part thereof.

In the drawing:

Fig. 1 is a front perspective view of a harmonica showing my new design.

Fig. 2 is an end elevational view thereof.

Fig. 3 is a rear perspective view thereof, on a reduced scale.

I claim:

The ornamental design for a harmonica, as shown.

JOHN VASSOS.
